UNITED STATES PATENT OFFICE.

FRED J. MILLER, OF DUDLEY, WISCONSIN.

LUMBER-BINDING CHAIN.

1,053,054.

Specification of Letters Patent. Patented Feb. 11, 1913.

Application filed May 22, 1912. Serial No. 699,054.

To all whom it may concern:

Be it known that I, FRED J. MILLER, a citizen of the United States, residing at Dudley, in the county of Lincoln, State of

5 Wisconsin, have invented certain new and useful Improvements in Lumber-Binding Chains; and I do hereby declare the following to be a full, clear, and exact description of the invention, such as will enable others 10 skilled in the art to which it appertains to make and use the same.

This invention relates to lumber binding chains and has for an object to provide a novel tightening lever for drawing the chain 15 taut about the logs, a further object being to provide a novel latch for locking the lever in operative position.

With the above object in view the invention consists of certain novel details of 20 construction and combination of parts hereinafter fully described and claimed, it being understood that various modifications may be made in the minor details of construction within the scope of the appended claim.

25 In the accompanying drawing forming part of this specification:—Figure 1 is a side elevation of the device. Fig. 2 is an end elevation of the device. Fig. 3 is a detail perspective view of the device applied. 30 Fig. 4 is a cross sectional view taken on the line 4—4 Fig. 1. Fig. 5 is a fragmentary detail view of the hooked end of the device.

Referring now to the drawing in which like characters of reference designate similar 35 parts, 10 designates the binding chain, and 11 designates the locking lever by means of which the chain is drawn taut about the logs. The lever is provided in one end with a transverse arcuate slot 12 through which 40 the terminal link at one end of the chain is engaged, and the lever is provided on the same end with a hook 13 which engages a link of the free end of the chain as shown in Fig. 1 after the chain has been wrapped 45 about the logs. By rocking the lever toward the fixed end of the chain both ends

of the chain are drawn together as shown in Fig. 3, and to lock the lever in this operative position the following mechanism is employed.

50 A latch 14 is provided at one end with an orifice 15 to receive one of the links of the chain, the latch being provided near its free end with an opening 16 to receive a reduced finger 17 formed on the end of the lever handle, the finger being provided with an opening 18 which is disposed below the latch when the latter is applied, and which is adapted to receive a divided spring pintle 19 carried upon a chain 20 which is secured 60 to the extreme free end of the latch.

When the latch is in operative position as shown in full lines in Fig. 1 the lever is locked in position to hold the chain taut upon the logs. To loosen the chain it is 65 simply necessary to remove the pintle 19 and disengage the latch from the lever handle as shown in dotted lines in Fig. 1 whereupon the lever may be swung in the direction of the free end of the chain to slacken the chain 70 and disengage the hook thereof from the free end of the chain.

What is claimed is:—

The combination with a binding chain, of a tightening lever provided in one end with 75 an arcuate slot securing one end of said chain, and provided on the same end with a hook adapted to receive and engage in a link of the chain near the free end of said chain, a latch secured to said chain near the 80 fixed end thereof, and having an orifice adapted to receive the handle end of said lever, and a pintle carried by said latch engageable through an orifice formed in said handle end and operating to detachably secure 85 said latch to said lever.

In testimony whereof, I affix my signature, in presence of two witnesses.

FRED J. MILLER.
